*Making Store-Pipe, &c,
Patented June 19, 1826*

Walter James

Letters Patent. Dated, June 19. 1826.

The schedule referred to in these Letters Patent and making part of the same, containing a description in the words of the said Walter James himself of his improvement in the machine for bending tire for carriages and other vehicles, metallic bands and hoops of all descriptions, stone pipes, factory cans, tin ware, &c.

This invention consists in producing a uniform curve of any diameter to tire for carriages and other wheels, metallic bands and hoops of all descriptions, stone pipes for factory cans, tin ware &c. by means of three rollers of suitable length, diameter, and shape, to perform the work required.

These rollers are placed in a suitable frame, two of which have different bearings as herein after described; the third or upper roller to be placed perpendicular to the centre between the other two in moveable boxes, operated by wedge or screw, taking it nearer to, or remove it further from the other two rollers, and being made fast at the proper distance, is put in motion by any sufficient power when the article to be bent is introduced & drawn between them to receive the curve required.

I first operated the machine with the rollers being placed between the posts or stands, containing the moveable boxes that support the upper roller which practices may be continued; but as in many cases it would be difficult to disengage the article bent, from the machine without removing the upper roller as an improvement, I have placed the two bottom rollers at one side of the said posts or stands, on bearings having different boxes which will admit of the rollers being placed nearer to, or farther from, each other, as the nature of the work may require. To prevent the upper roller from springing, it has at the end near where the operation is performed, a gland iron on which is placed a clasp passing to the bottom of the frame, and made fast by a wedge or screw, which clasp is to be removed and replaced at each at each article bent, if required. The rollers being thus situated, the article may

be slipped off at this end, and any number of the same thickness introduced beneath the same curve and removed in a similar manner, without any alteration of the upper roller. The shape of the rollers must correspond to that of the article to be bent, whether of a cylindrical or conical form; & so placed that their surfaces, at the nearest approach, shall be parallel to each other. In bending steel pipes and other articles calculated to be locked, the locks must be turned previous to the operation; and one part of the lock introduced into a groove in one of the bottom rollers, as in this case it will be necessary that each roller have grooves, lengthwise, to admit the parts to be locked beneath their surface, while in the act of bending; and should not the other part of the lock happen to meet the groove in the upper roller, the motion of the bottom rollers together with the article may be checked, by means of a catch wheel and dog, and the upper roller slide round until that part of the lock will fall directly into the groove. And in bending thin ware, which is raised upon one edge the rollers should have corresponding grooves around them to admit the projecting part beneath their surface.

In bending thin w^t, the bottom rollers in order to assist in drawing in the article to be bent, may receive motion from the upper roller by means of a band passing over the upper roller between and under the other two, and finally over a pulley which is regulated by a weight or other wise, in order to produce a proper tension.

The rollers of this machine may be placed in a horizontal or vertical position, and varied in size and proportion as judgment or fancy may dictate; but however placed or varied, still their application to the above specified purpose, is what I claim as my discovery and invention.
